(57) **CLAIM**

We claim the ornamental design for a lighting device with extendable light, as shown and described.

DESCRIPTION

FIG. 1 is a top perspective view of a lighting device with an extendable light in a retracted position, showing our new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof;

FIG. 8 is a front perspective view of the lighting device with the extendable light in an extended position; and,

FIG. 9 is a top view of the lighting device with the extendable light in the extended position.

The broken lines are provided to show portions of the lighting device with extendable light that form no part of the claimed design.
